EVERETT S. WOOD, OF HOPEDALE, MASSACHUSETTS, ASSIGNOR TO
DRAPER COMPANY, OF HOPEDALE, MASSACHUSETTS, A CORPO-
RATION OF MAINE.

FILLING-REPLENISHING LOOM.

SPECIFICATION forming part of Letters Patent No. 760,769, dated May 24, 1904.

Application filed February 19, 1904. Serial No. 194,368. (No model.)

To all whom it may concern:

Be it known that I, EVERETT S. WOOD, a citizen of the United States, residing at Hopedale, county of Worcester, and State of Massachusetts, have invented an Improvement in Loop-Controlling Devices and Yarn-Guides for Filling-Replenishing Looms, of which the following description, in connection with the accompanying drawings, is a specification, like characters on the drawings representing like parts.

This invention relates more particularly to automatic looms wherein the running shuttle, provided with an automatic self-threading device, is replenished with filling from time to time, a loom of this type forming the subject-matter of United States Patent No. 529,940 and others of later dates. In such looms the reserve supply of filling-carriers or bobbins is held in a filling-feeder, the latter being moved intermittently to bring the filling-carriers one by one into position to be transferred by suitable means from the feeder to the running shuttle, transfer being effected automatically while the shuttle is in the adjacent shuttle-box. The filling ends are suitably held at the outer end of the feeder, and after receiving a fresh filling-carrier the shuttle is picked, or shot across the lay to the opposite shuttle-box, the held filling end causing the filling to draw off from the filling-carrier and enter a longitudinal thread-passage in the threading device of the shuttle. Supposing that the filling enters such passage and beneath a suitable retaining-prong or other device, on the return shot of the shuttle the thread is or should be drawn beneath a horn, and thereby guided through an open passage into the side-delivery eye of the shuttle, and when this is accomplished the shuttle is completely threaded and the filling is delivered thereafter from said eye. In practical operation trouble has been experienced from thread breakage after the threading of the shuttle as described, due to the throwing forward of a loop of the thread from the tip of the filling-carrier onto the threading device or over the point of the shuttle when the shuttle is stopped in one of the shuttle-boxes. Such box is manifestly that one into which the

shuttle enters with the threading device at its leading end, and when the slack thread is thrown forward it may unthread the shuttle, or the bight of the loop may catch on the prong or some other part of the threading device or even around the shuttle-point and break as soon as tension is put upon the thread when the shuttle is next thrown from the box. In either case filling replenishment or stoppage of the loom is required.

Shuttle-threading devices have been provided with means to prevent unthreading, and they have also been variously constructed to prevent the catching of the loop when one is formed and thrown forward, such shuttle-threading devices being either of the automatic type for use in automatic filling-replenishing looms or of the type where the threading is effected by hand, but into a delivery-eye having an open entrance. The most effective of such devices have very largely eliminated unthreading; but when the filling is slack it will frequently be thrown forward when the shuttle is boxed, catching on some part of the shuttle, and the thread will be broken.

My present invention has for one of its objects the production of extremely simple but effective means for preventing such slack filling if thrown forward from being caught in the threading device of or on the shuttle itself, such means being independent of the shuttle, so that the latter may be equipped with any desired or suitable threading device either automatic or of the other type specified. As a matter of fact, the formation of a loop of dangerous length is in general prevented by my invention; but should a long loop be formed and thrown forward it is absolutely prevented from causing any damage either by catching or by unthreading.

In addition to the loop-controlling means my invention has for a second object the production of novel means to control the fresh filling end on the first shot of the shuttle following filling replenishment, whereby the proper entrance of the filling into the thread-passage of the threading device on the shuttle is greatly facilitated and made more sure.

The various novel features of my invention as embodied in one practical form thereof will be fully described in the subjoined specification and particularly pointed out in the following claims.

Figure 1 is a top or plan view of the replenishing side of a loom provided with automatic filling-replenishing mechanism of the type referred to with one embodiment of my present invention applied thereto, the filling-feeder being shown in part by dotted lines and the lay being represented as on its backward stroke just before the replenished shuttle is shot from the shuttle-box. Fig. 2 is a right-hand side elevation of the parts shown in Fig. 1, the filling-feeder, however, being shown in transverse section on the line 2-2, Fig. 1. Fig. 3 is a view similar to Fig. 1, but showing the lay farther back and the shuttle well along in its flight to show more clearly the operation of the means for facilitating threading after filling replenishment. Fig. 4 is a front elevation of the right-hand shuttle-box, showing the operation of the means for preventing slack filling from being thrown forward onto the shuttle; and Fig. 5 is a detail in plan, showing how the loop if formed is held from being thrown forward onto the shuttle.

30 The lay A³, having thereon a shuttle-box B, the breast-beam A¹⁰, to which is rigidly secured the stand A⁷ for the filling-feeder, comprising, essentially, plates or disks a' a', connected by a sleeve a³, rotatably mounted on a horizontal stud a⁶, secured to the stand, the transerrer f', mounted to rock on the stud f, the filling-carriers b, arranged circularly in the feeder and supported by the disks a' a', and the filling-end holder b' b² (shown in dotted lines, Fig. 1) may be and are all substantially as in United States Patent No. 529,940 and operating as therein provided, the means for intermittently effecting feed movement of said filling-feeder being all substantially as in United States Patent No. 664,790.

50 The shuttle S is provided with an automatically self-threading device T, having a longitudinal thread-passage t and a prong t' extended across the front end thereof, the filling in the operation of threading being drawn down into the passage t and beneath the prong t' as the shuttle is shot away from the replenishing side of the loom, and on the return shot the thread is drawn down into the usual side delivery-eye t^x of the shuttle, Fig. 4, in well-known manner to those skilled in the art.

60 In the present embodiment of my invention I secure to the feeder-stand a guard which is so located as to project just above the eye end of the shuttle when the shuttle has entered and been stopped in the shuttle-box at the replenishing side of the loom, the position of the guard at such time causing it to engage a loop, if formed, and prevent it from being

thrown forward onto the shuttle-point or the threading device. The guard is herein shown as a U-shaped bar 1, (see Figs. 1, 3, and 5,) having a long shank 2 extending from one side thereof to the feeder-stand, the outer opposite side of the guard being elongated toward the front of the loom, as at 3, and having a series of rearwardly-turned teeth 4 on its lower edge (see Fig. 2) for a purpose to be described. The guard is substantially horizontal, as shown in Figs. 2 and 4, and the shank 2 extends at right angles to the feeder-stand, said guard being located as near as possible to the top of the shuttle-box B without hitting it as the lay beats up. At its forward end the extension 3 of the guide is beveled or rounded off to a point, as at 5, Fig. 2. The shank can be secured to the stand in any suitable manner, and herein I have shown it as forming a prolongation of the pivot-stud 300, on which is pivotally mounted the yielding or cushioned buffer m, Fig. 2, constructed and operating as set forth in Patent No. 664,790, above referred to. When the shuttle is about to be picked from the box B on the backward stroke of the lay, the parts are in the relative position shown in Fig. 1, and the various parts assume this same position when the shuttle has just been thrown into said shuttle-box and stopped, except that then the lay is moving forward. If then we suppose the shuttle to have just been stopped, viewing Figs. 1, 4, and 5, should a loop t¹⁰ of filling be thrown forward off the tip of the filling-carrier such loop will hit the inner side of the guard 1 and will drop back and down either into the opening in the shuttle-body or onto the guard and will be pulled down and off as the lay completes its forward movement. In either case it will be manifest that the bight of the loop cannot fall onto the threading device T of the shuttle nor onto the point of the latter, the interposition of the guard absolutely preventing such action. For a similar reason the loop cannot unthread the shuttle, for such loop cannot be thrown forward beyond the inner side of the guard. When the lay is fully forward, the shuttle is beyond the guard; but the latter has by that time performed its office. If the loop should be extremely long, it would still be rendered harmless by the guard, for the latter would stop its forward throw, so that it could not catch on any part of the shuttle. The guard also serves as a guide for the filling immediately after filling replenishment and facilitates the entrance of the filling into the thread-passage t as the shuttle is picked from the replenishing side of the loom.

Referring to Fig. 1, it will be remembered that the endmost filling-carrier of the series is the one transferred to the shuttle, such endmost filling-carrier prior to transfer occupying the position represented at b^x, Figs. 1 and 2, and its filling end 50 is led around the edges

of the disks a' and b' to the central stud b^2 , and, as shown by dotted lines in Fig. 1, the filling-end is led at an angle to the axis of the feeder in order to give some slack when transfer is effected. It will be understood that the filling does not draw off (from the filling-carrier just inserted in the shuttle) in a line parallel with the feeder-axis, because the lay is moving back and the shuttle is traveling across the lay, so that such line will be diagonal from the edge of the disk b' to the shuttle. Again, as the lay moves back the transfer f' rises and the feeder is advanced, so that the point of engagement of the fresh filling end and the disk b' will advance from the point 51, Figs. 1 and 3, to 52, increasing the angularity of the filling relative to the lay and making it more difficult for the fresh filling to enter the thread-passage t . It will be supposed that in Fig. 1 the filling-carrier b^3 in the shuttle has just been inserted and that the lay has moved back to just about the picking-point, the feeder having advanced the next filling-carrier b^4 to the position shown. The filling end 53, extending from the filling-carrier b^3 around the disk b' to stud b^2 , passes under the guard 1 and is engaged by the teeth 4 on the lower edge of its outer side and is thereby held when the feeder advances to the position shown in Fig. 1. As the lay recedes and the shuttle is picked the filling then leads from the point 54 on the guide, Figs. 1 and 3, rather than from the point 52 on disk b' , and hence its angularity with relation to the shuttle-path is very much reduced, and it is held more approximately in line with the thread-passage t , facilitating its entrance thereto. By beveling the end of the guard extension 3 the filling end easily passes thereunder as the lay moves back.

It must be borne in mind that in the explanation of the action of the guide the lay is referred to as going back and the shuttle as just about to be picked in Fig. 1 while the loop-controlling office of the guard is performed on the forward beat of the lay just after the shuttle has been stopped in the box. The same illustration, however, serves to explain the action of both guard and guide when the shuttle is boxed, as there is no change in the relative position of the various parts, save that the feeder advances one step between transfer and the retrograde movement of the lay into the position shown. In Fig. 3, however, the shuttle is in its flight and the lay is moving back, the angle between the shuttle-path and the fresh filling end becoming smaller as the shuttle proceeds to the left.

My invention is not restricted to the precise construction and arrangement herein shown and described, as the same may be modified and rearranged in various particulars by those skilled in the art without departing from the spirit and scope of my invention as expressed in the appended claims.

Having fully described my invention, what I claim as new, and desire to secure by Letters Patent, is—

1. In a loom provided with automatic filling-replenishing mechanism, an automatically self-threading shuttle adapted to contain a filling-carrier, and means independent of the shuttle to prevent a loop of filling from being thrown forward off the tip of the filling-carrier when the shuttle is boxed. 75

2. In a loom provided with automatic filling-replenishing mechanism, a shuttle adapted to contain a filling-carrier and having an automatic self-threading device at its eye end, and independent means to extend over such end 80 of the shuttle when the latter is boxed, to prevent forward throw of a loop of filling from the tip of the filling-carrier onto the threading device.

3. In a loom provided with automatic filling-replenishing mechanism, an automatically self-threading shuttle adapted to contain a filling-carrier, and a guard located above the path of and adjacent the shuttle when stopped in the shuttle-box, to prevent a loop of filling 90 from being thrown forward onto the leading end of the shuttle. 85

4. In a loom, provided with automatic filling-replenishing mechanism, an automatically self-threading shuttle adapted to contain a filling-carrier, and a fixedly-mounted thread-guard adapted to extend across the shuttle in front of the tip of the filling-carrier therein when the shuttle is stopped in the shuttle-box. 95

5. In a loom, a shuttle of the self-threading type, and means independent of the shuttle to prevent slack filling from being thrown forward over the shuttle-eye when the shuttle is boxed. 100

6. In a loom, a shuttle having a delivery-eye with an open entrance, means to direct the filling thereto through said entrance, and means independent of the shuttle to prevent slack filling from being thrown over upon said directing means or the delivery-eye when the shuttle is boxed. 105

7. In a loom, a shuttle adapted to contain a filling-carrier and having an open delivery-eye, and means on the shuttle to automatically direct filling to said eye, combined with means mounted independently of the shuttle to prevent slack filling from being thrown forward off the tip of the filling-carrier onto the thread-directing means when the shuttle is boxed. 115

8. In a loom, a shuttle adapted to contain a supply of filling and provided with self-threading means, and a guard mounted independently of the shuttle and adapted to extend over the eye end thereof when boxed, to prevent filling 120 from being thrown forward over the threading means on the shuttle.

9. In a loom, a shuttle adapted to contain a filling-carrier and provided with a self-threading device, and a horizontal U-shaped station- 130

- ary guard adapted to extend across and above the shuttle when stopped at the end of its flight, to prevent a loop of filling from being thrown forward onto the threading device of 5 the shuttle.
10. In a loom provided with automatic filling-replenishing mechanism including a rotatable filling-feeder and its stand, an automatically self-threading shuttle adapted to contain a filling-carrier, and means mounted on the stand and adapted to extend across the shuttle in front of the tip of the filling-carrier when the shuttle is stopped, to prevent a loop of filling from being thrown forward 10 onto the shuttle.
11. In a loom, automatic filling-replenishing mechanism, including a filling-feeder and a filling-end holder, a shuttle adapted to contain a filling-carrier and provided with an automatically self-threading device, and means to engage and hold the fresh filling end at a point approximately in line with the thread-passage of the threading device during the 15 flight of the shuttle.
12. In a loom, automatic filling-replenishing mechanism, including a filling-feeder and a filling-end holder, a shuttle adapted to contain a filling-carrier and provided with an automatically self-threading device, and means to engage and temporarily hold the fresh filling end between the shuttle and the end holder and facilitate the coöperation of the filling 20 with the threading device during the flight of the shuttle.
13. In a loom, automatic filling-replenishing mechanism, including a filling-feeder and a filling-end holder, a shuttle adapted to contain a filling-carrier, and provided with an automatically self-threading device, and a combined guard and guide to prevent the throwing forward and catching of a filling-loop on the threading device, when the shuttle is boxed, and to guide a fresh filling end into co-operative relation with the threading device after filling replenishment. 25
14. In a loom provided with automatic filling-replenishing mechanism, a shuttle adapted to contain a filling-carrier and having an automatically self-threading device, and a U-shaped loop-controlling guard fixedly mounted above and adjacent the shuttle-path, the said guard having rearwardly-turned teeth on its lower edge, to engage and temporarily hold the fresh filling end after filling replenishment, and more effectively guide it into 30 coöperation with the threading device during the flight of the shuttle.
15. In a loom provided with automatic filling-replenishing mechanism, including a filling-feeder provided with means to hold the filling ends, a fixed guide to engage the filling end of a filling-carrier freshly inserted in the running shuttle and retain such filling end in position to facilitate automatic threading of the shuttle, and an automatically self-threading shuttle. 35
